UNITED STATES PATENT OFFICE.

ALBERT E. MAYNARD, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION.

LENS-DRILL.

1,196,572.

Specification of Letters Patent. Patented Aug. 29, 1916.

Application filed April 3, 1914. Serial No. 829,255.

To all whom it may concern:

Be it known that I, ALBERT E. MAYNARD, a citizen of the United States, residing at Southbridge, in the county of Worcester and State of Massachusetts, have invented 5 certain new and useful Improvements in Lens-Drills, of which the following is a specification.

My invention relates to improvements in 10 drills and has particular reference to a drill for use in piercing glass or the like.

The leading object of my invention is the provision of an improved means for supplying lens drilling fluid or melange, as it is 15 commonly termed, to the point on an ophthalmic lens at which the aperture is to be formed.

A further object of my invention is the provision of an automatically operating 20 melange feed for use in connection with an ophthalmic lens drill which will supply to the lens a predetermined amount of melange before the drill is brought into engagement therewith, and which will prevent the use 25 of an undue amount of said fluid.

A further object of my invention is the provision of an improved device of this character which may be adjusted to feed any desired amount of melange and which 30 may also be so operated as to feed an additional amount in any particular instance without interfering with the regular automatically supplied quantity.

Other objects and advantages of my im- 35 proved melange feed for drills should be readily apparent by reference to the following specification taken in connection with the accompanying drawings, and it will be understood that I may make any modifications 40 in the specific details of construction shown and described within the scope of the appended claims without departing from or exceeding the spirit of my invention.

Figure I represents a fragmentary per- 45 spective view of a drill equipped with my improved melange feed. Fig. II represents a fragmentary vertical sectional view of my device and the operating means carried in the adjacent portion of the drill arm. Fig. 50 III represents a perspective view partially in section illustrating the working parts of my invention.

In the drawings, the numeral 1 denotes 55 the frame for the lens drill having journaled therein the spindle 2 provided at its

lower end with the drilling point 3, a yoke or arm 4 operated by the handle 5 serving to control the vertical movement of the drill spindle. Disposed beneath the drill point 3 is a stand 6 and rest 7 for the lens 8 to be 60 drilled. These parts, it will be understood, may be of any usual construction, not particularly entering into my invention.

In the drilling of an ophthalmic lens it is desirable to make use of a small amount of 65 drilling fluid or what is commonly termed melange, but as this drilling is frequently done by the optician rather than by an ordinary shop workman, it is desirable to make use of as small an amount of fluid as possible, 70 both to prevent the same from being thrown by the centrifugal force of the drill onto the operator or the adjacent parts of the drill itself. It is also desirable to keep the surface of the lens as clean as possible and free 75 from the fluid to obviate the necessity for frequent cleaning and polishing of the lens with the attendant possibility of scratching or marring of the same. It is, therefore, particularly desirable in connection with 80 lens drills that a small amount of melange be delivered on the lens before it is engaged by the drill and that this melange be delivered only upon the point where the drill is to engage the lens and not be spattered or 85 unduly spread on the lens. It is, therefore, the purpose of my invention to automatically place a few drops of melange in correct position on the lens as the drill is moved downward into engagement therewith. To 90 attain this result I preferably secure to the drill frame 1 the tank 9 for the melange, which I have shown as provided with a pin 10 fitting into a slot 11 at the side of the frame and provided with a second threaded pin 12 fitting into another slot 13 of the frame, this second pin being provided with a thumb nut 14 which may be tightened to 95 lock the reservoir in position.

Formed in the bottom of the reservoir is 100 an aperture to receive the bushing 15 having the melange receiving passage 16 at one side thereof, and having its bore of variable diameters. This bore comprises the enlarged portion 17 adapted to receive the 105 plunger 18 and the actuating spring 19 therefor, the large portion of the bore terminating in a shoulder 20, the diameter of the bore for a distance below the shoulder 20 being substantially that of the plunger 110.

18 which makes a close fit therewith, this portion of the bore terminating in a seat 21 for the lower end 22 of the plunger, while below the seat 21 extends the outlet passage 23. The lower end of the bushing is preferably threaded to receive the cap 24 which secures in position the discharge spout 25, loosening of the cap permitting of adjusting of the position of the spout 25 to accurately control the point of discharge from the spout onto the lens, but it will be understood that if preferred the spout may be formed integral with the bushing and the coupling cap 24 dispensed with.

15 Rotatably held on the upper end of the bushing 15 is the female coupling 26, into which threads the cap plug 27 having the interior shoulder 28 bearing against the washer 29 on the plunger and having formed in one side the slot 30 adjacent to which are the ears 31, between which is pivotally supported by the pin 32 the trip 33. This trip has the V-shaped outer portion 34 for engagement with the latch 35 and has its inner end slotted as at 36 to engage the pin 37 of the plunger. The latch 35 is carried in a socket in the arm 4, being actuated by the spring 38 and having its outward movement limited by the pin 39.

20 30 In the operation of my improved melange feed as the handle 5 is shifted to bring the drill point 3 into engagement with the lens to be drilled, the latch 35 strikes the end 34 of the trip forcing the same downward, as illustrated in Fig. II. On this downward movement of the outer end of the trip the inner end through the slot and pin 37 raises the plunger, as indicated, against the pressure of the spring 19 having its upper end bearing against the stationarily held washer 29 and its lower end bearing against the washer 40 on the plunger. As the plunger is raised this lower end 22 rises above the passage 16 and allows the melange to flow 25 onto the chamber 41 and through the discharge passage 23 and spout.

25 35 It will be understood that ordinarily the movement of the arm 4 is fairly rapid; consequently the latch but temporarily engages the trip 34 before the continued downward movement forcing the same to spring back out of engagement therewith, which occurs but slightly after the parts reach the position shown in Fig. II. As the latch slips 40 out of engagement with the trip the spring 19 will force the plunger sharply downward and the small quantity of melange contained in the chamber 41 and passage 23 will be quickly expelled or squirted onto the correct 45 point on the lens. The portion 22 of the plunger will fit against the seat 21 forming a satisfactory valve for preventing further flow of the melange onto the lens, this valve action being supplemented by the side 50 of the plunger closing the mouth of the passage 16, as should be clearly understood by reference to Fig. II. On releasing the drill as the same moves into inoperative position, the beveled upper face of the latch 35 will engage the beveled or inclined lower face 70 of the trip 34 and the latch will be cammed backward against the tension of the spring 38 without in anywise disturbing the plunger.

55 If it is desired on a particular lens to make use of a greater amount of melange than that ordinarily employed, it is merely necessary to move the handle 5 and drill down slowly, when the latch will hold the trip and plunger raised for as long a period 80 as may be desired, and the melange will simply flow through the discharge spout in place of being ejected therefrom. To shut off the flow, it is merely necessary to continue the downward movement until the catch moves out of engagement with the trip.

60 To vary the amount of fluid ordinarily discharged it is only necessary to raise or lower the cap plug 27 so that the trip will remain in engagement with the latch either a longer or shorter period of time, according to the quantity of melange desired.

65 If preferred, in place of adjusting the cap plug 27 to regulate the amount of melange discharged I may employ the set screw 42 carried by said plug, screwing downward of the screw limiting the upward movement of the plunger and thus restricting the amount of melange passing through the passage 16 and chamber 41 while raising of the screw permits further upward movement of the plunger and thus an increased flow of the melange.

70 From the foregoing description it will be seen that I have provided a simple, inexpensive and practical construction which may be readily applied to drills now in use, or which may be constructed integral with a drill, if preferred, which will satisfactorily deliver a predetermined quantity of melange to a lens at a certain predetermined position in which the quantity delivered may be varied, as desired, by adjustment of the device, or may be varied merely by speed of manual operation in any particular instance, and which will prove extremely efficient and desirable in every particular.

75 I claim:

1. A melange feed for a lens drilling machine, including a tank, a discharge spout for the tank, a combined valve and feed plunger controlling communication between the tank and spout, means for resiliently forcing the plunger into closed position, a trip carried by the tank and operatively engaging the plunger, and a yieldingly mounted latch member carried by the drill and engaging the trip to operate the valve as the drill is moved in one direction, and

to yield without operating the plunger valve as the drill is moved in the opposite direction, substantially as illustrated.

2. The combination with a lens drill having a reciprocating drilling member, of a melange tank secured to the drill, a tubular member mounted in the tank and having inlet and discharge apertures, a discharge spout in communication with the discharge aperture, a plunger valve within the tubular member serving to control passage of fluid from the tank through the inlet aperture and to forcibly eject the fluid from the discharge aperture, means for resiliently forcing the plunger valve into closed position, a head carried by the tubular member, a stop device and a trip carried by the head and adapted to engage the plunger valve to control its movement, and a latch member carried by one of the reciprocating parts of the drill for engaging the trip member to actuate the plunger valve, substantially as and for the purpose described.

3. In a machine of the character described, a liquid retainer, an ejector valve therefor, an operating tool, means for advancing and retracting the tool, and means adapted to temporarily engage the valve and hold the same open for a limited period during the advance of the tool, said means being constructed to release the valve be-

fore the tool is advanced into operative position.

4. The combination with a lens drill including a frame and a drill shifting member, of a tank carried by the frame, a tube mounted within the tank and having an aperture near its lower end in communication with the tank, a cap engaged on the lower end of the tube beneath the tank and securing a discharge spout to the tube, a plunger valve within the tube adapted to control the discharge from the tube and when in depressed position to close the aperture near the lower end of the tube, a spring for normally holding the plunger valve in closed position, a head mounted on the upper end of the tube and provided with a pivoted trip member, the trip member and plunger valve having interlocking parts whereby rocking of the trip reciprocates the plunger, and a latch member on the drill shifting device adapted to contact with and rock the trip member and thus temporarily actuate the plunger valve, substantially as described.

In testimony whereof I affix my signature in presence of two witnesses.

ALBERT E. MAYNARD.
